(57) **CLAIM**

The ornamental design for a light box, as shown and described.

DESCRIPTION

FIG. 1 is a top perspective view of a light box showing my new design, shown sitting in a base which is shown in broken lines and forms no part of the claimed design;

FIG. 2 is a top perspective view of the light box of FIG. 1, showing my new design;

FIG. 3 is a side view of the light box of FIG. 2, with all side views being identical; and,

FIG. 4 is a top view of the light box of FIGS. 1 and 2, with the bottom view being identical.
